AUTOMATIC TRAIN-CONTROL SYSTEM.

1,360,749.

Specification of Letters Patent.

Patented Nov. 30, 1920.

Application filed December 4, 1915, Serial No. 65,070. Renewed March 27, 1919. Serial No. 285,636.

To all whom it may concern:

Be it known that I, WINTHROP K. HOWE, a citizen of the United States, and a resident of the city of Rochester, in the county 5 of Monroe and State of New York, have invented a new and useful Automatic Train- Control System, of which the following is a specification.

This invention relates to automatic train 10 control systems, and more particularly to such systems in which the movement of the train is controlled, in some way, by the energization and deenergization of a control relay carried on the train and governed by the 15 contact of a contact shoe carried by the train with contact rails or ramps fixed along the trackway, said ramps being energized or deenergized according to traffic conditions.

20 One of the principal objects of this invention is to devise a system for automatically controlling railway trains by the co-operation of contact shoes and contact rails which will permit the use in the same train 25 of a number of motor cars or locomotives each equipped with the automatic train control apparatus and which will allow the simultaneous operation of the control apparatus on all of said motor cars or locomotives, regardless of the number of these motor cars or locomotives, or of their position 30 in the train, or of the length of the blocks or the length of the train.

A further object of the invention is to de- 35 vice a system for automatically controlling railway trains by the co-operation of contact shoes and contact rails which will prevent an excessive or dangerous flow of current in cases where the train consists of two 40 or more motor cars or locomotives each equipped with the train control apparatus and connected together electrically by a continuous conductor so as to operate simultaneously, and where the train passes over a 45 block which is shorter than the length of said train.

Other objects and advantages will appear as the description of the invention progresses, and the novel features of the invention 50 will be particularly pointed out in the appended claims.

Generally stated, the invention consists in arranging a suitable current limiting device so that it can be placed in the controlling 55 circuit for each ramp along which the im-

proper or excessive current would flow, and in providing suitable means for placing said current limiting device in said controlling circuit whenever said improper current commences to flow.

The invention further consists in the parts, and in the arrangements and combinations of parts and of the controlling circuits therefor, which will be more fully set forth hereinafter.

In describing the invention in detail, reference is had to the accompanying drawing, wherein I have illustrated a preferred physical embodiment of my invention, and wherein like characters of reference designate corresponding parts throughout the several views, and in which:

The figure is a diagrammatic view of a train, and the track therefor, and shows the parts of the automatic train control system embodying the invention, both the parts which are associated with the train and the parts which are located along the trackway, the conditions assumed for this figure being such that an improper and excessive flow of current might result if it were not prevented by the means embodying this invention.

Referring to the accompanying drawing, one rail 1 of the trackway over which the train passes is electrically continuous, the separate rail sections thereof being suitably bonded together, and the other rail 2 of said trackway is divided into electrically distinct sections A, B, C, and D by means of suitable insulating joints 3. These blocks may be of any suitable length required to obtain the desired spacing of the trains. At the entrance to each block a ramp or contact rail R is supported in any suitable manner along the trackway, as for example, adjacent to the track rail 2, and so as to be insulated from said track rail.

The current for energizing the parts of the train control apparatus and their controlling circuits located along the trackway is derived from two main line wires 4 and 5 which are connected to a suitable source of current, as a generator 6. In the particular arrangement of the parts and controlling circuits illustrated in the drawing, the energy used as the operating medium is assumed to be alternating current.

The parts and electrical connections between said parts associated with each block and each ramp are the same, and for sim-

plicity and clearness these parts and electrical connections associated with the block C will be given the same reference characters as the corresponding parts of the block 5 B, with the distinctive exponent "1" added thereto. The normal direction of traffic is indicated by the arrow α .

Adjacent to one end of each block, preferably the exit end, is a track transformer 10 7, the primary of which is connected to the line wires 4 and 5, and the secondary of which is connected by wires 8 and 9 to the track rails 1 and 2, respectively. At the other end of each block is located a track relay 15 10 which is connected by wires 11 and 12 to the track rails 1 and 2, respectively, and which is provided with two circuit controlling armatures 13 and 14 represented according to the well known convention. The 20 track transformers 7 and the track relays 10, together with the track rails 1 and 2 of each block, constitute the well known normally closed track circuit, the operation of which will be apparent to those skilled in 25 the art.

The current for energizing the ramps R and for controlling the parts of the train control system carried by the train is supplied from a transformer 15 located adjacent to each ramp R. The primary of each transformer 15 is connected to the line wires 4 and 5, and one terminal of the secondary of said transformer 15 is connected by a conductor 16 to the electrically continuous 30 track rail 1, said secondary being provided with two taps 17 and 18 by means of which suitable voltages necessary for the proper operation of the system may be obtained.

In the particular physical embodiment of 40 the invention illustrated in the drawing, the current limiting device is an impedance 25 which is connected in a partial controlling circuit for each ramp, as explained more fully hereinafter. Each impedance 25 is arranged so that it can be shunted or included 45 in its corresponding ramp controlling circuit, and the shunt around the impedance 25 is opened and closed by the movement of an armature 19 of a suitable relay or translating device S. This relay S is shown as the type 50 known in the art as a polyphase alternating current relay and comprises two separate coils or windings which are shown in the drawing according to established convention. One coil 20 of the relay S is connected by conductors 21 and 22 to the secondary of a transformer 23, which has its primary connected to the line wires 4 and 5, so that the coil 20 of the relay S is energized at all times. 55 The other coil 24 of the relay S is included in the same controlling circuit as the impedance 25. The type of the relay S shown is well known in the art, and to obtain a clear understanding of the nature and 60 operation of this invention it is not deemed 65

necessary to describe the construction of this relay S in detail; and the characteristic features of this relay, in so far as they are necessary for a clear understanding of the invention, will be pointed out fully in the 70 description of the operation. For the purposes for which the relay S is used in this invention, this relay is preferably constructed so as to be quick acting, and the armature 19 and coöperating contacts 75 controlled thereby are designed so as to be able to interrupt a comparatively large current without injury.

The conductors and the electrical connections between the different operating parts 80 of the train control system which are located along the trackway will not be described in detail, since these electrical conductors and the different operating circuits will be fully set forth hereinafter in the description of the 85 operation.

Referring to the parts of the train control system which are carried on the train, the train is shown diagrammatically as comprising two pairs of wheels 28—28, 26—26 90 connected by the usual axles 29 and 27 respectively; and these pairs of wheels and axles are connected by a bar 30 which represents the frame or body of the cars or locomotives constituting the train. The wheels 95 and axles illustrated are assumed to represent those in different cars or locomotives, each of which is provided with suitable train control apparatus; and since this train control apparatus is constructed the same on 100 each motor car or locomotive, a description of one will suffice for all, and corresponding parts will be designated by the same reference characters.

A bracket 31 of suitable insulating material is supported in any appropriate manner on each motor car or locomotive and is shown fastened to one of the journal boxes or axles; and mounted on the bracket 31 is a vertical movable plunger or shoe 32, which 110 is pressed downwardly by a spring 33. The shoes 32 on the different motor cars or locomotives are arranged in the same plane as the ramps R so that, as the train passes along the track, said shoes 32 will contact 115 with said ramps. The shoes 32 are designed to make electrical contact with the ramps R, and also to be lifted in a way to actuate a suitable circuit controlling device carried on the train; and to accomplish this purpose, 120 the shoe 32 is shown provided with an insulating button 34 arranged to lift a contact spring 35 out of contact with a contact piece 36, when the shoe 32 is raised. The contact spring 35 and the contact piece 36 are fixed 125 to the bracket 31, and since said bracket is assumed to be of insulating material, said contact piece 36 and said contact spring 35 are electrically independent, except when the contact is closed.

The automatic control of the train is obtained by the operation of a suitable train control device, which is designated generally in the diagrammatical illustration by the reference characters K. This device K may be of any suitable construction, and since its particular construction forms no part of the present invention, and since various devices well known in the art possess its necessary functions and are capable of being used in a system embodying this invention, it is deemed unnecessary to illustrate or describe the device K further in detail. The device K may be constructed and arranged so as to apply the brakes on the train immediately upon its operation, or after a certain interval; or the operation of the device K may be made dependent in any suitable way upon the speed at which the train is traveling, or upon the speed of the train and the distance between the train and the point of danger. In the particular embodiment of the invention shown the device K is arranged so as to be set into operation when the electrical energy which is normally supplied to it is interrupted, and the device K is restored to its normal or inactive condition when electrical energy is again supplied to it. The deenergization and reenergization of the device K is controlled by an armature 39 of a control relay 37 carried on the train; and when the control relay 37 is energized, and its armature 39 is raised to its upper position, electric current is supplied to the device K from a source of current carried by the train, as a battery 40, by a circuit which may be traced as follows:

Circuit Number One.

From the battery 40, conductor 41, device K, conductor 42, armature 39 of the control relay 37 in its upper position and conductor 43 back to the battery 40. When the shoe or plunger 32 is in its lower or normal position, the control relay 37 is supplied with current from a local source of current carried by the train, as a battery 44, by a circuit which may be traced as follows:

Circuit Number Two.

From the battery 44, conductor 45, relay 37, conductors 46 and 48, armature 38 of the control relay 37 in its upper position, corresponding to the energized condition of said control relay, conductor 49, contact spring 35, contact piece 36 and conductors 50 and 51 back to the battery 44.

The control relay 37 is also controlled by an alternating current pick up or preliminary energizing relay 52 having an armature 53, and connected by conductors 54 and 55 to the secondary of a transformer 56 carried on the train. One terminal of the pri-

mary of the transformer 56 is connected by a conductor 57 to the bar 30 which represents the frames of the cars constituting the train, and the other terminal of the primary of the transformer 56 is connected by a conductor 58 to the contact shoe 32. The terminals of the primaries of the transformers 56 which are connected to the shoes 32 on the different motor cars or locomotives of the train are connected together by a continuous conductor or bus 59.

When the alternating current pick up relay 52 is energized and its armature 53 is raised to its upper position, the control relay 37 is energized by current from the battery 44 according to a circuit which may be traced as follows:

Circuit Number Three.

From the battery 44, conductor 45, control relay 37, conductors 46 and 60, armature 53 of the relay 52 in its upper position and conductors 61 and 51 back to the battery 44.

Operation: In general, the operation of the system of train control herein disclosed is the same as that described at length in my prior application Serial No. 38,132, filed July 6, 1915, and for a clear understanding of the nature of the present invention, it is sufficient to explain briefly the operation of the system for a few cases of different traffic conditions. In making this explanation, the action of the cutout relay S will be at first disregarded, the armatures 19 being assumed to be in their normal closed position.

For the first traffic condition to be considered, assume that the train in question is about to enter the block B; that this train has found the trackway unobstructed and has been able to proceed at unlimited speed without any restriction being imposed upon it by the train control device K; and that neither of the blocks B or C is occupied. Under these conditions, the track relays 10 and 10¹ of the blocks B and C, respectively, are energized from the corresponding track transformers, as will be clearly understood by those skilled in the art of railway signaling. Since the track relay 10 is energized, its armature 13 is in its upper position, and a high difference of potential exists between the ramp R and the track rail 1 according to a circuit which may be traced as follows:

Circuit Number Four.

From the ramp R, conductor 62 armature 13 of the track relay 10 in its upper position, conductor 63, high voltage tap 18 of the secondary of the transformer 15 and conductor 16 to the track rail 1.

When the first shoe 32 of the train engages the ramp R it is raised and lifts the

contact spring 35 out of contact with the contact piece 36, thereby breaking the circuit Number Two which normally maintains the control relay 37 energized. At the same time that the shoe 32 is raised to interrupt circuit Number Two, said shoe makes electrical contact with the ramp R, so that current is supplied to the primary of the transformer 56 carried by the first car 10 of the train according to a circuit which may be traced as follows:

Circuit Number Five.

From the high voltage terminal or tap 18 15 of the secondary of the transformer 15, conductor 63, armature 13 of the track relay 10 in its upper position, conductor 62, ramp R, contact shoe 32, conductor 58 to the primary of the transformer 56, conductor 57 to 20 the frame 30 of the car and thence by the wheels and axles to the track rail 1 and by conductor 16 back to the other terminal of the secondary of the transformer 15.

The current flowing in the primary of the 25 transformer 56, being alternating in character, induces a like alternating current in the secondary of said transformer which passes through the relay 52, energizes it and raises its armature 53 to close the pick up circuit 30 Number Three for the control relay 37. In this way, at the same time that circuit Number Two which normally maintains the control relay 37 energized, is broken by raising the shoe 32, another circuit Number Three 35 for energizing said control relay 37 is established; and consequently the armatures 38 and 39 of said control relay are maintained in their upper position, and the train control device K remains idle or inactive.

40 When the first wheels and axle of the train pass from the block A and enter the block B, the track relay 10 will be deenergized, as will be clearly understood by those skilled in the art of railway signaling; and the armature 13 of said track relay 10 will drop and interrupt the circuit Number Five which energizes the alternating current relay 52. Since the block C is assumed to be unoccupied, the track relay 10¹ is energized 45 and its armature 14¹ is in its upper position, so that a low difference of potential will be created between the ramp R and the track rail 1 and energize the primary of the transformer 56 and consequently the alternating current pick up relay 52, according to a circuit which may be traced as follows:

Circuit Number Six.

60 From the low voltage tap 17¹ of the secondary of the transformer 15¹, conductor 67¹, armature 14¹ of the track relay 10¹ in its upper position, conductors 66¹ and 65¹, armature 19¹ of the relay S¹ in its closed 65 position, coil 24¹ of the relay S¹, conductor

64, armature 13 of the track relay 10 in its lower position, conductor 62, ramp R, shoe 32, conductor 58, primary of the transformer 56, conductor 57, frame 30 of the car and thence by the wheels and axles to the track rail 1 and by conductor 16¹ back to the other terminal of the secondary of the transformer 15¹.

The alternating current pick up relay 52 is so designed that, when its armature 53 is 75 in its upper position, the current induced in the secondary of the transformer 56, when the low difference of potential is applied to its primary according to circuit Number Six, is sufficient to hold the armature 53 in 80 its upper position; but such current is not sufficient to cause said armature 53 to be raised from its lower position. In other words, it is necessary to apply high voltage to the primary of the transformer 56 in 85 order to cause the relay 52 to raise its armature 53 from its lower position; whereas a low voltage across the primary of the transformer 56 is sufficient to maintain the armature 53 in its raised position. This characteristic of the relay 52 may be obtained in a 90 number of different ways, as will be readily appreciated by those skilled in the art; and, consequently, a detail description of a suitable construction for the relay 52 is deemed 95 to be unnecessary.

From the foregoing it can be seen that when neither of the blocks B nor C are occupied by a train, and a train passes from the block A into the block B, the control relay 100 37, if deenergized, will be reenergized, or if energized, will remain energized; and consequently train control device K is not set into operation.

For the next condition of traffic to be considered, assume that a train is in the block A and is about to enter block B; that this train has found the trackway unobstructed and has been traveling unrestricted by the train control device K; and that, while the 110 block B is not occupied by a train, a train occupies the block C. Under these conditions, as the train approaches the ramp R and its first shoe 32 engages said ramp, a high difference of potential will exist between 115 the ramp R and the track rail 1 according to the circuit Number Four hereinbefore set forth; and, consequently, the control relay 37 will remain energized. When the first wheels and axle of the train pass from the 120 block A into the block B, the track relay 10 is deenergized and there will be no difference of potential between the ramp R and the track rail 1, since it is assumed that a train occupies the block C and causes the track 125 relay 10¹ to be deenergized and its armature 14¹ to drop and interrupt the circuit Number Six hereinbefore set forth. Since the raising of the shoe 32 broke the circuit Number Two which normally holds the control relay 130

37 energized, and since there is no difference of potential between the ramp R and the track rail 1, such as would energize the alternating current pick up relay 52 so as to close 5 the other circuit Number Three for energizing the control relay 37, said control relay 37 is totally deenergized and its armatures 38 and 39 will drop. When the armature 38 of the control relay 37 drops, it opens a break in 10 the circuit Number Two which normally energizes the control relay 37, so that after the shoe 32 has left contact with the ramp R and said circuit Number Two is closed at the shoe, nevertheless, said circuit Number Two 15 will not be reestablished. When the armature 39 of the control relay 37 drops, it breaks the circuit Number One which normally energizes the control device K; and consequently, said control device K is set 20 into operation to control the train.

From the foregoing it can be seen that when the block C is occupied by a train and a following train enters the block B, the control device K on the following train will be 25 set into operation. With this general description of the operation of the parts of the system, which description of the operation will be found fully amplified in said application, Serial No. 38,132 hereinbefore 30 mentioned, the particular arrangement of devices and circuits, with which this invention deals more particularly, can be pointed out.

Assume that the train includes two or 35 more motor cars or locomotives, each of which is provided with a contact shoe 32, a control relay 37, an alternating current relay 52, and the associated electrical devices and connections, said devices being electrically 40 connected by the continuous conductor or bus 59; and further assume that said train is long enough to span the distance between two successive ramps so that the contact shoe of two different motor cars or locomotives 45 are in contact with the two ramps at the same time. Disregarding for the moment the operation of the relays S and assuming that their armatures 19 are in their closed position, with the condition such as assumed, 50 it can be seen that there is established a path of comparative low resistance including part of the secondary of the transformer 15¹, said path being as follows:

55 Circuit Number Seven.

Commencing at the high voltage tap 18¹ of the secondary of the transformer 15¹, conductor 63¹, armature 13¹ of the track relay 10¹ in its upper position, conductor 62¹, ramp R¹, shoe 32 of the front car, conductors 58 59, and 58, the shoe 32 of the rear car, ramp R, conductor 62, armature 13 of the track relay 10 in its lower position, conductor 64, coil 24¹ of the relay S¹, armature 65¹ of the relay S¹ in its closed position, con-

ductors 65¹ and 66¹, armature 14 of the track relay 10¹ in its upper position and conductor 67¹ to the low voltage tap 17¹ of the secondary of the transformer 15¹.

There is also established another conduct- 70 ing path for current to flow which includes the other part of the secondary of the trans- 75 former 15¹, said path being the same as the circuit hereinbefore described and design- 80 ated circuit Number Six. Also, there is es- 85 tablished a conducting path along which current may flow which includes both parts of the secondary of the transformer 15¹, said path being analogous to the circuit herein- 90 before described and designated circuit 95 Number Five, this path for the ramp R¹ being as follows:

Circuit Number Eight.

From the high voltage tap 18¹ of the sec- 85 ondary of the transformer 15¹, conductor 63¹, armature 13¹ of the track relay 10¹ in its upper position, conductor 62¹, ramp R¹, front contact shoe 32, conductor 58, primary of the transformer 56, conductor 57 to the 90 frame 30 of the front car and thence by the wheels and axles to the track rail 1 and by conductor 16¹ back to the other terminal of the secondary of the transformer 15¹.

It should be noted that the low voltage 95 tap 17¹ and the high voltage tap 18¹ are of the same polarity at any given instant, and for convenience it will be assumed that these 100 taps are both positive, as marked on the drawing.

Assuming the same conditions as illus- 105 trated in the drawing, that is, that the two ramps R and R¹ are being touched at the same time by the shoes of two separate cars included in the same train, it can be seen 110 from a study of the circuits, hereinbefore set forth and designated six and seven, that these circuits, which are both established under the particular conditions assumed, have parts in common, namely, the con- 115 ductor 67¹, the armature 14¹, conductors 66¹, 65¹, armature 19¹, coil 24¹, conductor 64, arma- 120 ture 13, conductor 62, shoe 32 and conductor 58. At the point where the conductor 58 connects with the primary of the trans- 125 former 56 these two circuits Numbers Six and Seven divide, the circuit Number Six passing through the primaries of the dif- 130 ferent transformers on the several cars of the train, while circuit Number Seven passes along the bus 59, conductor 58 to the ramp R¹ and thence to the high voltage 18¹ of the transformer 15¹. In fact, the circuits Num- 135 bers Six and Seven are arranged according to the well known three-wire system of dis- tribution, the parts including conductor 67¹, and so forth, which are common to these two circuits being in effect the neutral wire of this three-wire system; and, as is well known, current will flow in this neutral wire 130

in one direction or the other, depending upon the resistances of the parts of the circuit Number Six and the circuit Number Seven which are not common to each other, 5 and the relative values of the voltage between the conductor 16¹ and the low voltage tap 17¹, and the voltage between the low voltage tap 17¹ and the high voltage tap 18¹. It can be seen that the parts of circuit Number 10 Seven which are peculiar to it namely, conductors 63¹, 62¹, 58 and 59, are comparatively low resistance conductors; whereas the parts of circuit Number Six which are peculiar to it include the primaries of the 15 transformers 56 on the several motor cars or locomotives of the train. Consequently, the flow of current in the two circuits Numbers Six and Seven is not balanced and with the voltages and resistances which are considered to be best adapted for practical 20 operation, it is found that a relatively large current flows in the conducting path from the ramp R through the coil 24¹ of the relay 21 to the low voltage tap 17¹ in the direction 25 indicated by the arrow b. In other words, it may be said that a part of the secondary of the transformer 15¹ between the tap 17¹ and the tap 18¹ is practically short circuited; and this short circuiting not only causes an 30 improper and excessive current to flow through said secondary and the other parts of the circuit, but also prevents the proper energization of the pick up alternating current relays 52 by circuit Number Eight, even 35 though traffic conditions are such that said relays should be energized. The relays 52 are not properly energized under the particular conditions assumed for the reason that instead of a large current derived from 40 the high voltage source flowing through the primaries of the transformers 56 on the several cars of the train, the current flowing through the primaries of said transformers is practically all derived from the low voltage 45 source only and is too small to pick up the relays 52.

For these reasons, the above described short circuit should be avoided in order to save the wiring and apparatus from injury 50 by the excessive current flowing and also to prevent unnecessary delay to the train by a failure to restore the train control apparatus to its normal condition, although it is proper to do so.

55 In the above discussion of the short circuit of part of the secondary of the transformer 15¹, the action of the relay S¹ was disregarded; but it can be seen that under the conditions assumed current is flowing 60 through the coil 24¹ of the relay S¹ in the direction indicated by the arrow b. As pointed out hereinbefore, the relay S¹ is of the type commonly known as a polyphase relay; and one characteristic of this type 65 of relay, which is well known to those skilled

in the art of railway signaling, is that the rotor or armature actuating member of said relay may be caused to turn in one direction or the other according to the phase relation of the currents flowing in the respective 70 coils or windings of said relay. Under ordinary and normal conditions, when a train first enters the block B, current flows in the circuit Number Six from the low voltage tap 17¹ of the secondary of the transformer 15¹ 75 to the ramp R through the coil 24¹ of the relay S¹ in the direction indicated by the arrow a. In short, normal and proper current flows through the coil 24¹ in the direction indicated by the arrow a; whereas 80 the improper and excessive current flows in the direction indicated by the arrow b. The relay S¹ is so designed that when the proper current flows through its coil 24¹ in the direction indicated by the arrow a, the phase 85 relation between that current and the current in the coil 20¹ of said relay is such as to cause the armature 19¹ of said relay to close and remain in its closed position. On the other hand, when the excessive and improper 90 current flows through the coil 24¹ of the relay S¹, the phase relation of that current and the current flowing in the coil 20¹ of said relay is such as to move the armature 19¹ to its open position. When the armature 19¹ is 95 opened, the normally closed low resistance shunt around the impedance 25¹ is interrupted, so that all of the excessive current flowing along conductor 66¹ must pass through the coil 24¹ along conductor 69¹ 100 through the impedance 25¹ and along conductor 68¹ in order to reach the conductor 64. The impedance 25¹ is so proportioned according to the voltage between the taps 17¹ and 18¹ of the secondary of the transformer 15¹ and according to the resistances and impedances of the other parts of the circuits Numbers Six and Seven that said impedance 25¹ will limit the flow of improper 105 current to an amount small enough not to do any damage and yet large enough to maintain the coil 24¹ of the relay S¹ energized. If desired the impedance 25¹ instead of being a separate impedance external to the winding of the relay S¹ may be made a part 115 of the winding of said relay; and when the impedance 25¹ is so made a part of the winding of the relay S¹, it assists in holding the armature 19¹ open and also has its impedance materially increased by reason of this 120 location.

From a consideration of the circuits shown and hereinbefore traced it can be seen that, in effect, there are two partial circuits associated with each ramp, one of said partial circuits including the entire secondary of the transformer 15 associated with that ramp, and the other partial circuit including part of the secondary of the transformer 15 associated with the succeeding ramp; and 130

further that the current limiting impedance 25 and the relay S are included in said second mentioned partial circuit.

The parts of the automatic train control 5 system shown and described are arranged and designed to be operated by alternating current, but it is to be understood that by a simple modification, which will be apparent to those skilled in the art of railway signal- 10 ing; these parts may be so constructed and arranged that direct current may be used as the operating medium. Also, although only two motor cars or locomotives are illustrated in the drawing, any number of motor cars or 15 locomotives may be included in the train without affecting the operation or effectiveness of the system. Various other changes in the particular arrangement of parts and controlling circuits therefor which are 20 shown and described may be made without departing from the invention or the particular physical embodiment thereof.

Although I have particularly described the construction of one physical embodiment 25 of my invention, and explained the operation and principle thereof; nevertheless, I desire to have it understood that the form selected is merely illustrative, but does not exhaust the possible physical embodiments 30 of the idea of means underlying my invention.

What I claim as new and desire to secure by Letters Patent of the United States, is:

1. In an automatic train control system, 35 in combination: insulated contact rails located along the trackway for said trains; a source of current associated with each contact rail; a partial circuit including said source of current, said contact rail and a 40 track rail of said trackway; current limiting means; and means interposed in said partial circuit and responsive to a predetermined direction of flow of current therein for connecting said current limiting means 45 into said partial circuit.

2. In an automatic train control system, in combination: insulated contact rails located along the trackway for said trains; a source of current associated with each of 50 said contact rails; a partial circuit including said source of current, said contact rail and a track rail of said trackway; current limiting means interposed in said partial circuit; a normally closed shunt for said current 55 limiting means; and means interposed in said partial circuit and responsive to a predetermined direction of flow in current therein for opening said shunt.

3. In an automatic train control system, 60 in combination; insulated contact rails located at intervals along the trackway for said trains; two sources of current connected in series and associated with each contact rail; a partial circuit including both of said 65 sources, the corresponding contact rail and

a track rail of the trackway; a second partial circuit including one of said sources of current, the preceding contact rail and a track rail of the trackway; current limiting means; and a polarized translating device 70 interposed in said second partial circuit and operated by a flow of current therein in a predetermined direction for connecting said current limiting means into said second partial circuit.

4. In an automatic train control system, in combination: a trackway divided into electrically isolated blocks; an insulated ramp located at the entrance of each of said blocks; a source of current and a track relay 80 associated with each block and forming with the track rails of that block a normally closed track circuit; separate sources of current associated with each ramp; a partial circuit associated with each ramp and closed 85 when the track relay of the block protected by that ramp is energized for connecting one of said sources of current across the trackway and said ramp; a second partial circuit associated with each ramp and closed 90 when the track relay of the block protected by that ramp is energized and the track relay of the preceding block is deenergized; said second partial circuit connecting the other source of current across the track 95 rails and the preceding ramp; current limiting means; and means operated by a flow of current in said second partial circuit in a certain direction for interposing said current limiting means in said second partial 100 circuit.

5. In an automatic train control system, in combination: an insulated ramp; a partial circuit for establishing a difference of potential between said ramp and the track 105 rails of the trackway for the trains; and current limiting means operable upon the flow of current in one direction interposed in said partial circuit.

6. In an automatic train control system, 110 in combination with a train including a number of vehicles each having a contact shoe, said contact shoes being electrically connected together, of automatic train control apparatus on each vehicle controlled 115 by a partial circuit terminating at the corresponding contact shoe and the wheels of the vehicle, contact rails located at intervals along the track, two sources of current connected in series and associated with each 120 contact rail, a partial circuit including both of said sources, the corresponding contact rail and a track rail, a second partial circuit including one of said sources, the contact rail next in the rear and a track rail, 125 and current limiting means operable upon a flow of current in a certain direction in said second partial circuit and interposed in said second partial circuit.

7. In an automatic train control system, 130

in combination with a track divided into track circuit blocks, a contact rail located adjacent to the entrance end of each block, a partial circuit including a source of current and terminating at the contact rails of two successive blocks, said partial circuit being established when a train occupies the block between these contact rails, and means included in said partial circuit and operable upon the flow of current therein for limiting the flow of current in said partial circuit.

8. In an automatic train control system, in combination with a track divided into track circuit blocks each having a track relay, a contact rail associated with each block, a partial circuit for each contact rail terminating at that contact rail and a track rail, said partial circuit including a source of current, a back contact in the track relay of the corresponding block and a front contact of the track relay of the second block in advance, and means operatively responsive to the polarity of the current flowing in said partial circuit for limiting the flow of current therein.

9. In an automatic train control system, in combination with impulse transmitting means located at intervals along the track, a circuit including a source of current and established under safe traffic conditions for governing each impulse transmitting means, and means included in said circuit and acting automatically upon a flow of certain current therein for obstructing such flow of current, said means being unaffected by current flowing in said circuit from said source.

10. In an automatic system for protecting railway traffic, the combination with a contact rail located adjacent to the railroad track and insulated therefrom, of a partial circuit including a source of current and terminating at said contact rail and a track rail, said partial circuit being established under certain traffic conditions along the track, means in said circuit for opposing the flow of current therein, a shunt for said means offering comparatively no opposition to the flow of current in said circuit, and electromagnetic means responsive to a particular flow of current in said circuit for controlling said shunt.

11. In an automatic system for protecting traffic on railroads, the combination with a contact rail located adjacent to the railroad track and insulated therefrom, of a partial circuit including a source of alternating current and terminating at said contact rail and a track rail, an impedance included in said circuit, a normally closed shunt for said impedance, and electromagnetic means acting automatically upon a flow of current of a predetermined character in said circuit for opening said shunt.

12. In an automatic system for protecting traffic on railroads, the combination with a train including a number of vehicles each having a contact shoe, a conductor electrically connecting the contact shoes of the train, automatic train control apparatus on each vehicle connected between said conductor and the frame of the vehicle, contact rails located at intervals along the track and having their electrical conditions dependent on traffic conditions in advance thereof, and means along the track for automatically limiting the flow of current from one contact shoe to another contact shoe on the train.

13. In an automatic train control system, a trackway impulse device, a circuit for energizing said device, and current limiting means in said circuit operable automatically upon the flow of current in a predetermined direction therein.

14. In an automatic train control system for railroads having tracks divided into blocks each provided with a track circuit, an impulse device on the track near the entrance to each block, a circuit for energizing each device governed by the track circuit of the block next in advance, and current limiting means for said circuit operable automatically by a predetermined flow of current therein.

15. In an automatic train control system, a trackway impulse device, a circuit including a source of alternating current for energizing said device, an impedance, circuit controlling means adapted to include said impedance in said circuit, and a polyphase relay for operating said means.
